Samuel M. Gaffney

ATTORNEY.

UNITED STATES PATENT OFFICE

WALTER F. HEROLD, OF UPPER MONTCLAIR, NEW JERSEY, ASSIGNOR TO THE BASICK COMPANY, OF BRIDGEPORT, CONNECTICUT, A CORPORATION OF CONNECTICUT

CASTER

Application filed July 9, 1927. Serial No. 204,493.

The present invention relates to improvements in casters, particularly of the type adapted for use with hollow metal posts of bedsteads, or the like, and in which the pintle carrying caster element is adapted to be inserted in an open socket frame having an apertured bottom bearing base and a top bearing, either lateral or axial thrust.

It is particularly proposed to provide an improved pintle construction cooperating with the frame so that upon insertion of the pintle it will be positively guided into its proper relation with the top bearing, and to this end the present embodiment of the invention consists in providing a pintle adapted to be retained in the frame by means cooperating between the frame and pintle, and in such relation to the pintle and top bearing that it will not become effective until the pintle is in properly engaged or aligned relation with the top bearing. Heretofore such retaining means took effect before engagement or alignment with the pintle or its top bearing, with the result that very often the weight of the furniture was let down as soon as the pintle was retained, but before it was properly aligned or in engagement with its top bearing, so that it would very often jam in the frame before it could be guided into relation with the top bearing, necessitating lifting the furniture and re-inserting the pintle, and very often damaging the frame structure, so that it had to be replaced.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a perspective view of a caster and spring frame according to one embodiment of the invention.

Fig. 2 is a vertical sectional view of the same, inserted in a furniture leg and with the pintle of the caster partially inserted, that is, inserted to the point where its upper end is in engagement with the top bearing, but the pintle retaining means has not as yet become effective.

Fig. 3 is a similar view showing the caster fully inserted.

Fig. 4 is a vertical sectional view of a modified form of the invention in which the top bearing is in the form of a center thrust bearing, and showing the pintle in partially inserted relation.

Fig. 5 is a similar view and showing the pintle in fully inserted relation.

Similar reference characters indicate corresponding parts throughout the several figures of the drawings.

Referring to the drawings, the caster, according to the embodiment of the invention, disclosed in Figs. 1 to 3, comprises a spring frame and leg mount unit adapted for insertion in a tubular furniture leg; and a pintle caster unit adapted for insertion and removal with respect to the spring frame and leg mount unit. The spring frame and leg mount unit consists of a circular base plate provided with a central pintle receiving aperture 11, flanged upwardly as at 12, to provide a combination thrust and journal bearing for the pintle, as will hereinafter more fully appear.

The base plate 10 is provided at its periphery with a downwardly bent flange portion 13 and an upwardly bent rim 14, the latter adapted to abut and engage beneath the end of the furniture leg. The pintle retaining split spring ring 15, preferably of the type disclosed in my co-pending application Serial No. 120,670, filed July 6, 1926, is mounted at the upper edge of the flange 12 and retained in a centrally apertured cup member 16 secured to the base plate by means of lugs 17 engaged through diametrically opposed slots 18 in the plate, and bent over on the under surface, the aperture of the cup member being of the same diameter as the aperture 11 of the base plate, and with it constituting a relatively long journal bearing for the pintle, which in addition to its better bearing surface, is of greatly increased strength. The diameter of the ring is such that its inner edge normally projects within the pintle bearing opening and is adapted to frictionally grip upon the surface of the pintle to yieldably retain it, being freely rotatable

100

within the cup member during swivelling action of the caster.

The spring frame member 19, of inverted U-shape, is formed from flat sheet metal and is provided at its upper transverse portion with a dome shaped pintle guide portion 20, pressed upwardly therein and provided with a central flanged aperture 21 which, in the connected relation of the frame to the leg mount base, is aligned with the central aperture of said base and is adapted to be engaged by the upper end of the caster pintle. The portion 20, in addition to providing a pintle guide surface, reinforces the top of the frame so that it is inherently rigid. The lower edges of the side legs of the spring frame are connected to the base plate in such manner as to permit inward and outward contraction and expansion of the side legs, and for this purpose I have shown the side legs of the present embodiment provided with downwardly projecting locking extensions 22 engaged in diametrically opposite openings or slots 23 provided in the base plate and bent inwardly on the under surface of the base plate.

The caster wheel unit consists of the usual horn 24 having a wheel 25 carried therein upon an axle 26, and having a pintle 27 secured in its upper transverse portion. The pintle is provided at its base, adjacent the horn, with a flange 28 having a filleted shoulder 29 at its upper edge, which provides a combination thrust and journal bearing having contact with the turned edge of the flange 12. The pintle is furthermore tapered intermediate its ends, as at 30, so that its upper end is of reduced diameter to facilitate insertion through the retaining ring 15, which in its normal contracted relation is of larger diameter than said reduced diameter pintle portion. The lower portion of the pintle, however, expands the ring, so that the latter is gripped thereon, and during swivelling of the caster rotates therewith in loose relation within the cup member 16.

The clearance of the bearing aperture 11 and the bearing aperture of the cup member 16, with respect to the pintle, is such that the latter may be inserted at an angle to its normal vertical position. The domed guide portion 20, however, engages and confines the upper end of the pintle so that it is guided into the central aperture 21, as shown in dotted lines in Fig. 2, thereby facilitating the manual insertion of the pintle.

The particular feature of the present invention consists in the construction of the pintle, and its relation to the retaining means, i. e. the spring ring 15 and the upper bearing aperture 21, its purpose being to insure the manual insertion of the upper end of the pintle in the aperture 21 before the ring grips upon the enlarged diameter base portion of the pintle, and to this end, the reduced por-

tion of the pintle is of such length that it will still be in relation to the spring ring when the upper end of the pintle is engaged in the aperture 21, and at this point the pintle may be fully inserted, thereby bringing the enlarged diameter base portion of the pintle into relation with the retaining ring which retains the pintle against dropping out, as clearly shown in Fig. 3. In constructions heretofore in use, where the retaining means became effective before engagement of the pintle with its top bearing, the person inserting the caster would very often let the weight of the furniture down as soon as the pintle was retained, with the result that the pintle would vary often jam against the top of the spring frame or socket before the pintle could engage its top bearing. The present construction, on the other hand, practically compels full insertion of the pintle in proper relation to its top bearing before the furniture can be let down, inasmuch as the pintle will be unretained and will drop out unless the same is first engaged with the top bearing.

In Figs. 4 and 5 I have illustrated a modified form of socket frame in which the pintle has axial thrust bearing at its upper end with an inverted cone shaped bearing 31 formed in the upper end of the frame, the upper end of the pintle being indented, as at 32, for this purpose. A dome shaped guide portion 33 surrounds the bearing 31, extending slightly below the level of its lower end, and is adapted to guide the pintle into engagement therewith. According to the invention, the reduced diameter portion of the pintle is of such length that the upper end of the pintle enters the guide portion 33 before engagement of the enlarged diameter portion with the retaining ring 15, as shown in Fig. 4, thereby insuring proper engagement with the bearing 33 upon full insertion of the pintle, as shown in Fig. 5.

While I have shown the top bearing portion for the pintle, in Figs. 1 to 3, as consisting of the flanged aperture 21 and its guide portion 20, and the top bearing portion, in Figs. 4 and 5, as consisting of the inverted cone shaped bearing 31 and its guide portion 33, it will be understood that the invention contemplates, with respect to the top bearing portion, any other type of top bearing, either with or without an associated guide portion, where a non-pintle-confining space exists between the top bearing portion and the base.

I have illustrated and described a preferred and satisfactory embodiment of the invention, but it will be obvious that changes may be made therein, within the spirit and scope thereof, as defined in the appended claims.

Having thus described my invention, what I claim and desire to secure by Letters Patent is:

1. In a caster, a furniture leg engaging ele- 130

- ment including a top bearing portion, a laterally extending pintle guide portion extending below said top bearing portion, and an apertured bearing base, a removable caster element including a pintle adapted to be engaged through said aperture of the base and to be engaged with said pintle guide portion, a pintle retaining split spring ring carried by said leg engaging element adapted to grip said pintle to retain it, a portion of said pintle being of smaller diameter throughout its length than the opening of said ring and adapted to pass freely therethrough, another portion of said pintle being of larger diameter than the opening of said ring and adapted to be gripped thereby, said smaller diameter portion being of such length that said ring is ineffective until said pintle is in engaged relation with said top bearing portion.
2. In a caster, a furniture leg engaging element including a top bearing portion and an apertured bearing base, a removable caster element including a pintle adapted to be engaged through said aperture of the base and to be engaged with said top bearing portion, a pintle retaining split spring ring carried by said base, said pintle having an enlarged diameter portion in proximity to its base and adapted to be gripped by said ring to be retained thereby and a small diameter cylindrical portion of smaller diameter throughout its length than the opening of said ring and adapted to pass freely through said ring and said smaller diameter portion being of such length said ring is ineffective until the pintle is in engaged relation with said top bearing portion.

Signed at Bridgeport, county of Fairfield, and State of Connecticut, this 28th day of June, 1927.

WALTER F. HEROLD.
